INVENTOR.

Z. E. JONES

BY
Victor J. Evans
ATTORNEY

UNITED STATES PATENT OFFICE.

ZEDDIE E. JONES, OF SAN FRANCISCO, CALIFORNIA.

TELEPHONE ATTACHMENT.

Application filed February 12, 1927. Serial No. 167,773.

This invention relates to improvements in telephone attachments and has particular reference to a valve for a telephone transmitter.

5 The principal object of this invention is to produce a device which will cut off extraneous noise from entering the transmitter of a telephone.

10 Another object is to produce a device which may be attached to any standard telephone transmitter.

A further object is to produce a device which will normally remain in open position, to be closed only when desired.

15 A still further object is to produce means which will enable the user of the phone to hear more plainly when using the instrument.

20 Other objects and advantages will be apparent during the course of the following description.

In the accompanying drawings forming a part of this specification and in which like numerals are employed to designate like parts throughout the same,

25 Figure 1 is a fragmentary view of a telephone transmitter having my device attached thereto and partly shown on cross section, and

30 Figure 2 is a front elevation of my device.

In using a telephone, it is often difficult to hear due to the fact that extraneous noises enter the transmitter, working back over the line into the receiver through which the 35 person is listening. It also often occurs that the person using the instrument wishes to close off the transmitter while holding a conversation with another person, which conversation it is desired that the party 40 at the other end of the line should not hear.

Referring to the drawings wherein for the purpose of illustration is shown a preferred embodiment of my invention, the numeral 5 designates an upper portion of a telephone stand having a transmitter 6 of the usual construction. This transmitter is provided with a face plate 7 having a threaded opening 8. It is into this threaded opening that the usual mouth piece 9 is 45 screwed.

50 My device consists of a cylindrical member 11 having a threaded end 12 attached to engage the threads 8 of the face plate 7. The member 11 is also internally threaded 55 so as to receive the threaded portion 13

of the mouth piece 9. Positioned within the cylindrical member 11 is a pivoted member 14 having a disc 16 secured to a portion thereof. This pivoted member embodies in its construction an upper portion on which the disc is mounted and has a lower portion 17, defining a handle, whereby the disc may be manipulated. A spring 18 is secured to the handle 17 and to the cylindrical member 11. This spring is so attached that it tends to keep the disc 16 in the open position shown on the dotted line in Figure 1.

The manner of using my device is as follows:

The customary mouth piece 9 is removed from the transmitter after which my device is screwed therein. The mouth piece is then screwed into my device so that the assembly appears as shown in Figure 1. When the user of the phone desires to close the valve so that extraneous noises will not pass from the mouth piece to the diaphragm of the phone, he pushes upon the handle 17 against the tension of spring 18 which causes the disc 16 to take up the position shown in 75 Figure 2, thereby entirely blocking the passage through which any noise might pass.

80 It will thus be seen that I have produced a device, simple in construction, economical to manufacture and one which is well within the purchase price of the average user.

85 It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I 90 claim:

1. In combination with a telephone transmitter having a face plate and mouth piece, of a cylindrical member adapted to be secured between the face plate and mouth piece, a member including an upper portion diametrically extending through said cylindrical member and pivoted therein, a disc secured to said upper portion for partial rotary movement in a horizontal plane in 100 said cylindrical member, and a handle formed with said upper portion whereby the disc may be moved to close said cylindrical member and means for normally retaining said disc in open position. 105

2. In combination with a telephone transmitter having a face plate and mouth piece, of a cylindrical member having threaded ends for threadedly securing the same to the face plate and to threadedly receive the mouth piece in a manner whereby the cylindrical member is disposed between the face plate and mouth piece, a member vertically arranged through said cylindrical member and pivoted therein, a disc secured to the pivoted portion of the vertically arranged member for closing the cylindrical member, a handle included in said vertically arranged member for moving the same on its pivot and for partially rotating said disc for closing the cylindrical member and a coil spring surrounding the vertically arranged member and having its ends secured to the cylindrical member and vertically arranged member respectively for normally retaining said disc in open position.
3. In combination with a telephone transmitter having a face plate, of a cylindrical member adapted to be secured at one end to the face plate, a member extending diametrically through said cylindrical member and
4. In combination with a telephone transmitter having a face plate, of a cylindrical member, means for securing the same to the face plate, a member extending diametrically through said cylindrical member and pivoted therein, a disc secured to said diametrically disposed member for closing the passage through said cylindrical member, an operating handle included in said diametrically disposed member for moving the same on its pivot and for partially rotating said disc for closing the cylindrical member, and means for normally retaining said disc in a given position with reference to the inner wall of the cylindrical member.

In testimony whereof I affix my signature.

ZEDDIE E. JONES.
